UNITED STATES PATENT OFFICE.

JESSE THEODOR PYLE, OF AMARILLO, TEXAS.

SHEET-PILEING.

No. 876,808.

Specification of Letters Patent.

Patented Jan. 7, 1908.

Original application filed August 16, 1906, Serial No. 330,823. Divided and this application filed January 14, 1907.
Serial No. 352,161.

To all whom it may concern:

Be it known that I, JESSE THEODOR PYLE, a citizen of the United States, and a resident of Amarillo, in the county of Potter 5 and State of Texas, have invented a new and Improved Sheet-Piling, of which the following is a full, clear, and exact description, this being a division of my former application, Serial No. 330,823, filed August 16, 10 1906.

This invention relates to certain improvements in sheet piling adapted to be driven into sand or soft earth and serve to support the surrounding material while excavations 15 are being made, foundations laid, and other similar work carried on.

The piling is made up of a plurality of units which may be filled with concrete and serve as a foundation for buildings, bridges and 20 the like, or may serve merely as a temporary supporting wall during construction. The sheets are made up of a large number of sections or units which are sunk one at a time, each succeeding one being interlocked 25 with the next adjacent one as it is brought to the desired position. It is old to employ separable sections of this kind in the construction of piers, and it is further old to form these sections in a large circle or ring 30 and to excavate the material from inside the inclosure, but trouble is experienced in effecting a tight joint between the adjacent sections.

The object of the invention is to provide certain improvements in the construction of 35 the units, whereby the joint formed by the adjacent sections is substantially watertight, and whereby the device may be employed for coffer-dam work and the like.

A further object of the invention is to 40 provide means whereby an inclosure of any suitable shape and size may be formed and the gap between the first and last units respectively, closed irrespective of its width. To accomplish this object, the web of certain 45 of the units is so constructed that the width of the unit may be varied at will.

A further object of the invention is to provide means whereby the first of the unit sections may be driven and the material 50 simultaneously excavated from within said section.

The invention consists in certain features of construction and combination of parts, all of which will be fully set forth hereinafter 55 and particularly pointed out in the claims.

Reference is to be had to the accompany-

ing drawings forming a part of this specification, in which similar characters of reference indicate corresponding parts in all the figures; in which

Figure 1 is a transverse section of one form of my improved unit; Fig. 2 is a transverse section of a modified form of my improved unit; Fig. 3 is a diagrammatic plan of a bridge piling, showing one arrangement of sections; Fig. 4 is a transverse section of a unit provided with an extensible web; Fig. 5 is a transverse section of a unit provided with a modified form of extensible web and means for excavating the tube of said unit; 60 Fig. 6 is a side elevation of the form shown in Fig. 5.

The simplest form of section which I employ, comprises a tube 1 having a slot 2, extending along one side throughout its entire 65 length, and having a web 3, extending from the tube along its entire length on the side opposite to the slot. At the end of the web is a head 4, whose shape in cross section is substantially a sector of a circle, and adapted 70 to fit the inside of the tube of the next adjacent section, while a flange adjacent the head passes through the slot of this section. On the web 3 and adjacent the head 4 are 75 two flanges 5 which may be integral with the web or of separate pieces rigidly secured thereto, which flanges extend in the arc of a circle and spaced from the surface of the head 80 at a distance slightly greater than the thickness of the wall of the adjacent tube. These 85 flanges fit the outer wall of the tube adjacent the slot therein and serve to prevent the web of one section from extending more than the desired distance into the slot of the tube on the next adjacent section.

These sections 90 are driven into the sand one at a time, and as each one is driven a jet tube 6 is inserted into the tube 1 of the section and the material within the tube is either forced or pumped out of said tube. It will be noted that after 95 the first tube is inserted, the slot in the second will be closed by the head 4 of the first, while the second is being inserted and the material may be easily removed from the tube of said second and each succeeding 100 section, but at the time the first section is driven, it is necessary to provide certain means for closing the slot to prevent sand from coming into the tube as fast as it is removed by the jet tube 6.

In Figs. 5 and 6, I have shown a jet tube 6, having a plurality of bands 7 surrounding

the same, and each band attached to a short web 8, having flanges 9 fitting the outer surface of the tube. As the first section is driven into the sand it carries the jet tube 5 with its bands 7 and slot-closing means 8 and 9, so that the sand may be removed from the section and other sand prevented from entering the slot. After the first section is inserted, this particular means is no 10 longer necessary in connection with the other sections and a simple jet tube is freely inserted within the tube of the second and each succeeding section to remove the material therefrom. As soon as one section is 15 driven and the material removed from the tube, the latter is filled with concrete to strengthen and rigidly hold the same in place. These sections are usually driven in the arc 20 of a circle and as the last section is about to be inserted it is often found that the distance between the sections on the opposite sides of the remaining gap is greater or less than the normal width of a section, and to accommodate for this, I provide certain sections 25 having extensible webs, whereby the distance between the tube and the head of said section may be made greater or less to exactly fill the space between the adjacent sections. This may be accomplished by 30 making the web of two layers held together by rivets 10 passing through slots in the two layers, as illustrated in Fig. 5, or one portion of the section may have two adjacent web members 3^a between which a web member 3^b of the other portion of the section is 35 adapted to slide, the three members being held together by rivets passing through slots as in the form above described. The modification of the extensible web is clearly illustrated in Figs. 5 and 6. A single ring of 40 these sections is entirely inadequate and even dangerous. When it is desired to sink a pile to any considerable depth and to strengthen the pile, I preferably drive sections to form two concentric rings 11 and 12, as shown in Fig. 3, said rings being spaced 45 and held rigid by radial partitions 13. Both of the rings, and also the partitions are made up of the unit sections above described, 50 but in order to secure the partitions 13 to the concentric rings 11 and 12, I provide a form of section shown in Fig. 1, in which the web 3 has a branch web 14 rigidly secured at an angle thereto, whereby the tube 15 is driven 55 simultaneously with the tube 1 and junction between two rows of sections at an angle with each other is thereby perfected.

In certain forms of piers it is sometimes 60 desirable to have two rows of sections intersecting each other, as shown at 16 in Fig. 1, and I provide the form of section shown in Fig. 2 to be used in cases of this kind. This form of section has two branch webs 14 attached to the main web 3, and one of said 65 branch webs carries a head 4, said head and

tube being at substantially the same distance apart as are the head and tube of the normal unit section. In driving the sections to form a pier of the shape shown in Fig. 3, the material is excavated from each 70 of the inclosed spaces 17 as soon as the walls forming one of said spaces are completed and the space filled with concrete. The space within the inner ring of sections is likewise excavated and filled with concrete, so that the completed pier is a solid 75 mass of concrete having the sections embedded therein, said section having been employed merely as a coffer-dam to hold the surrounding material in place while the concrete pier was being filled in.

It is evident that the improved form of sections above described may be employed for placing the concrete foundations in sand to any depth, and is particularly useful where quicksand is encountered. The sections may be employed either for placing concrete piers, bridges, or foundations of buildings, or for any other similar purpose. For coffer-dam work the sections are employed as in the building of concrete piers, but the spaces 17 inclosed by the sections are not filled with concrete, and the row of sections surrounds the place where it is desired to place any suitable structure on 90 the river or lake bed, and when said structure is perfected, the sections may be removed without the same having been injured in any way, and said sections may be again employed for similar work.

Having thus described my invention, I claim as new and desire to secure by Letters Patent:

1. A section for sheet piling, comprising a tubular member having a slot extending longitudinally thereof, a web on the opposite side of said member from the slot, means on the end of the web adapted to extend through the slot of a similar tubular member and engage with the interior thereof, and means on the web adjacent said last mentioned means and adapted to fit against the outer wall of the next adjacent tubular member.

2. A section for sheet piling, comprising a tubular member having a slot extending longitudinally thereof, a web on the opposite side of said member from the slot, the outer edge of said web being adapted to extend through the slot of a similar adjacent tubular section, and means adjacent the edge of said web and adapted to engage with the interior and exterior of the tubular member of said adjacent section.

3. A section for sheet piling, comprising a tube having a slot extending the entire length thereof, a web on the opposite side of said tube from the slot, a head on the end of the web adapted to fit within the tube of the next adjacent section, and flanges on

the web adjacent said head, adapted to fit against the outer walls of the tube of the said next adjacent section.

4. A section for sheet piling, comprising a tube having a slot extending the entire length thereof, a web secured to said tube, a head on the end of said web adapted to fit within the tube of the next adjacent section, and means whereby the width of said web may be varied.

5. A section for sheet piling, comprising a tube having a slot extending the entire length thereof, a web extending along the opposite side of said tube, a head on said web, a jet tube adapted to extend within said tube, and means carried by said jet tube for closing said slot.

6. A section for sheet piling, comprising a tube, a web extending along one side of said tube, means on the end of said web whereby it may be attached to the tube of the next adjacent section, and a jet tube adapted to be inserted within said tube and by which the material may be removed therefrom.

25 7. A section for sheet piling, comprising a tube having a slot the entire length thereof, a web on said tube extending the entire length thereof, a second web secured to the first mentioned web at an angle thereto, heads on the ends of said web and said branch web adapted to fit within the tubes of the next adjacent sections, and flanges on said webs adjacent said heads adapted to fit against the outer walls of the tubes of the 35 said next adjacent sections.

8. An extensible sheet piling made in sections, each section having members extensible one relative to the other in the direction of the width of the section.

40 9. An extensible sheet piling having a section comprising two members each provided

with a body terminating in a head, the body of one member slidably engaging the body of the other member.

10. An extensible sheet piling having a section comprising two members each provided with a body terminating in a head, the body of one member slidably engaging the body of the other member, and means for fastening the bodies of the members together.

11. An extensible sheet piling having a section comprising two members each provided with a body terminating in a head, one of the members being made in two parts fastened together, the two-part body forming a recess for the reception of the body of the other member.

12. An extensible sheet piling having a section comprising two members, each provided with a body terminating in a head, one of the members being made in two parts fastened together, the two-part body forming a recess for the reception of the body of the other member, and means for fastening the two parts of the one member together.

13. An extensible sheet piling having a section comprising two members each provided with a body terminating in a head, one of the members being made in two parts fastened together, the two-part body forming a recess for the reception of the body of the other member, and means for fastening the bodies of the two members together after the desired adjustment is made.

In testimony whereof I have signed my name to this specification in the presence of two subscribing witnesses.
